UNITED STATES PATENT OFFICE.

CAMILLE AMEYE, OF ISEGHEM, BELGIUM.

APPARATUS FOR STERILIZING AND SATURATING LIQUIDS WITH CARBONIC ACID.

SPECIFICATION forming part of Letters Patent No. 634,790, dated October 10, 1899.

Application filed November 29, 1897. Serial No. 660,113. (No model.)

To all whom it may concern:

Be it known that I, CAMILLE AMEYE, a citizen of the Kingdom of Belgium, residing at Isegem, Belgium, have invented certain new and useful Improvements in Processes of and Apparatus for Sterilizing and Saturating with Carbonic - Acid Gas Liquids Contained in Casks or Like Vessels; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention has relation to apparatus for sterilizing or sterilizing and aerating or carbonating liquids.

The primary object of this invention lies in the provision of means whereby the contents of a storage or dispensing vessel may be sterilized or sterilized and carbonated; and one of the essential features of invention consists in a coil of pipe constructed for introduction into such vessel through the filling-aperture thereof, so that a heating agent may first be passed through such coil to heat the contents of the vessel to a sterilizing temperature, and so that after the completion of this operation a cooling agent may be passed through said coil to cool the contents of the vessel, after which said contents may be carbonated.

A further object of my invention lies in the connection of a coil of pipe such as above referred to with inlet and outlet passages in a stopper for the filling-aperture of the vessel, in means for passing a heating agent or a cooling agent at will through said stopper and coil, and in means for moving the vessel and therethrough keeping its contents in motion to expedite the heating or the cooling and to keep the contents (especially when malt liquors are treated) from acquiring a burned taste, which would be the case if the liquor were quiescent.

The invention has for its further object the provision of means for passing a heating or a cooling agent at will through the aforementioned coil and stopper and the provision of means for passing air or carbonic-acid gas through the stopper after the heating and subsequent cooling of the contents of the vessel.

The invention has for its further object the provision of means for collecting gases evolved from the liquid treated and educting the same to avoid overpressures, to include a gas-collector and a pressure-reducer in the air or gas circuit, the reducer discharging into the collector, and the latter communicating directly with the interior of the vessel through the aforementioned stopper; to provide means for educting the gas collecting in said collector during the heating of a liquid to be treated, so that said collector will act as an expansion - chamber during the aerating or carbonating operation to further reduce the pressure of the air or gas, and to combine with the appliances means for moving the vessel containing the liquid to be treated, so as to keep its contents in motion during three operations of heating, cooling, and aerating or carbonating.

The invention has for its further object a revolute shaft, a main circuit for a heating and a cooling agent having its inlet and outlet through said shaft and including the aforementioned stopper and coil, a branch circuit for air or gas having its outlet through said stopper and including the aforesaid gas-collector and pressure - reducer, means for passing a heating or a cooling agent at will through the main circuit, means for cutting off the communication between the stopper and its coil and the inlet to the main circuit and for establishing communication between said inlet and the branch circuit, means for passing air or gas through said branch circuit, and means for supporting a vessel or vessels containing liquid to be treated from the aforesaid revolute shaft.

Finally, the invention has for its object the provision of means for securely connecting a vessel or vessels, as a cask or casks or a barrel or barrels, to said shaft, so as to cause the same to revolve with the shaft; but that my invention may be fully understood I will describe the same in detail, reference being had to the accompanying drawings, in which—

Figure 1 is an end elevation of my improved apparatus, the supporting-framework being only partly shown. Fig. 2 is a section taken on line A B of Fig. 1. Fig. 3 is a section taken on line C D of Fig. 2. Fig. 4 is a top plan view of the apparatus. Fig. 5 is a like view

of the pressure-regulator. Fig. 6 is a section on the line E F of Fig. 5, and Fig. 7 is an elevation of one of the clamping-plates.

In bearings 2 on standards 1 of a suitable framework is mounted a shaft 3, which carries a fast and a loose pulley 4 and 5, respectively, said shaft having two passages 3^a and 3^b formed therein and extending from its ends toward its longitudinal center. To the passage 3^a is connected fluid-tight a supply-pipe 6, supported from an arm 1^a, projecting from one of the frame-standards 1, the connection being a well-known one and such as to allow the shaft to revolve freely on said pipe 6, which has three branches 6^a, 6^b, and 6^c, respectively, each provided with a stop-cock. The branch 6^a is for connection with a suitable source of hot-water or steam supply, according as one or the other is used as a means for heating the contents of a holder or holders to a sterilizing temperature, the branch 6^b for connection with a suitable source of refrigerant-supply, as cold water, and the branch 6^c for connection with a suitable source of carbonic-acid-gas supply.

To the passage 3^b in shaft 3 is connected fluid-tight an exhaust-pipe 7, supported from an arm 1^b, projecting from another standard 1 of the main frame, the connection of said exhaust-pipe being also well known and such as to allow shaft 3 to revolve freely on said pipe 7, which has two branches 7^a and 7^b, each provided with a stop-cock, the branch 7^a serving for the discharge of condensed steam or hot water and for the discharge of the refrigerant and the pipe 7^b for the escape of gas.

The apparatus shown in the drawings is constructed to receive and support two barrels 8 and 8^a, the supporting appliances being constructed and arranged as follows: A base-plate 9 is bolted to a two-part standard 10, each of said parts having a semicircular recess 10^a, forming a bearing for the shaft 3, and each of said halves has two arms 10^b projecting laterally therefrom, said arms having each a vertical slot 10^c. The two halves of the standard are bolted together below and above the shaft-bearing, so as to rigidly connect said standard with the shaft and cause it to revolve therewith. The base-plate 9 has internally-threaded sleeves, in which work screws 11, acting on skids or supporting-platforms 12, provided with concave seats for the barrels 8 and 8^a, and to said base-plate 9 are secured arms carrying hooks 9^a for chains 13, there being two such chains for each barrel. It is obvious that when the chains are passed around a barrel near its opposite ends and hooked to hooks 9^a on the base-plate and the tightening-screws 11 are rotated in the proper direction the skids 12 force the barrels against the chains, thus firmly securing said barrels near both ends. To further secure said barrels to their support, I provide clamping devices, which consist of head-plates 14, each having two radial arms 14^a, on which

are mounted shoes 14^b, so as to slide thereon. The upper face of these shoes is convex and beveled to fit against the barrel-heads and the ends of the barrel-staves, and by mounting them so as to slide on the radial arms of the plates 14 barrels of different sizes can be clamped to the described supporting devices. These plates 14 are clamped to the barrel-heads on the one hand by means of the slotted diverging arms 10^b on the two-part bracket-standard 10, against which bear the plates 14, applied to the proximate heads of the two barrels, and on the other by means of clamping-plates 15, applied to the plates 14 on the outer heads of said barrels and clamping-screws 16, acting on said plates 15 and working in a cross-head 17, carrying headed rods 18 at its opposite ends, which rods extend through the slots 10^c in the diverging arms 10^b of the bracket-standard 10. It is obvious that when the clamping-screws 16 are rotated in the proper direction the cross-head 17 is drawn away from the barrel, while the arms 10^b in bracket-standard 10 and the clamping-plates 15 are moved toward each other, thus clamping the barrel firmly, so that in conjunction with the chain-fastenings above described the barrels 8 and 8^a are firmly connected with the bracket-standard, and as the latter is rigidly secured to the shaft 3 said barrels will revolve therewith when power is applied to the fast pulley 4.

The shaft 3 carries a radially-arranged pipe 18, that communicates with the passage 3^a in said shaft, and is provided with a two-way cock 18^a, said pipe having a branch 18^b for purposes which will be presently described. A similar pipe 19 communicates with the passage 3^b of shaft 3 and is provided with a two-way cock 19^a, having a branch 19^b for purposes presently to be described. The outer end of pipe 18 has two branches for flexible pipes 21 and 21^a, connected with the inlet branch of pressure-regulators 20, whose said inlet branches are provided with stop-cocks 23 and 24. That portion of the pipe 18 above its stop-cock 18^a is removable, so that the removable section 18^c can be shifted from said pipe 18 and connected with the pipe 19, Fig. 3, for purposes presently to be described.

The pressure reducer or regulator 20, Figs. 5 and 6, consists of a comparatively shallow circular casing divided horizontally into two chambers 25 and 26 by a partition 20^a, and said chambers are placed in communication with each other through ports in the circular wall of the casing and through curled or coiled pipes 20^b of very small internal cross-sectional area, whereby the stream of carbonic-acid gas under pressure flowing into receiving-chamber 25 is not only divided, but its speed of flow, and hence the pressure under which the gas flows into the delivery-chamber 26 is materially reduced. This pressure is further reduced as the gas passes from the pressure-reducer into the gas-collector, which

in the carbonating of the gas acts as an expansion-chamber, as will be readily understood.

The delivery-chamber 26 of the pressure-reducers is connected with a gas-chamber 27, which carries a bung which is preferably detachably secured thereto. These bungs 34 and 35 have a through-passage 28 and separate inlet and outlet passages and branches.

10 The inlet branch of one of the bungs 34 closing bung-hole of barrel 8 is connected by a flexible pipe 29 with the branch 18^b, Fig. 1, of pipe 18, and the outlet branch of said bung is connected by a flexible pipe 30, Fig. 2, with 15 the inlet branch or bung 35 closing bung-hole of barrel 8^a, the outlet branch of which bung 35 is connected by a flexible pipe 31 with the branch 19^a of pipe 19, the circuit from pipe 18 to pipe 19 being completed by pipes 32 and 20 33, coiled into a corkscrew shape, the terminals of pipe 32 being secured to bung 34 to connect its inlet and outlet passages, respectively, and the terminals of the pipe 33 are similarly connected to bung 35, so that in applying 25 said bungs to their bung-holes the said pipes will be wholly within their respective barrels.

The object in coiling the pipes 32 and 33 in the form of a corkscrew is to secure as extensive 30 a superficial area as possible with a limited cross-sectional area of the coil and also to admit of the coils being screwed into the barrels through the bung-holes.

The operation of the apparatus is as follows: A couple of barrels, the contents of which are to be sterilized or sterilized and carbonated, are secured to the skids 12 by the means hereinabove described, the corkscrew pipes 32 33 being inserted into the barrels 35 and the bung-holes thereof tightly closed by means of the bungs 34 and 35. The stop-cocks 23 and 24 in the connection between pipe 18 18^c and the pressure-reducers 20 are closed, the stop-cock 18^a set to establish communication between pipe 18 and flexible pipe 29, and the stop-cock 19^a in pipe 19 set to establish communication between said pipe 19 and flexible pipe 31. A circuit is thus established from passage 3^a in shaft 3 through pipe 50 18, corkscrew pipes 32 33, pipe 19, and passage 3^b in said shaft 3, and by opening the stop-cock in branch 7^b of exhaust-pipe 7 and stop-cock in branch 6^a of feed-pipe 6 hot water or steam will flow through the described 55 circuit and escape through branch 7^b, thereby heating the contents of the barrels.

The operation of heating can be materially expedited by revolving the shaft 3 and the barrels so as to continuously displace the 60 contents of the latter about the pipes 32 and 33. In this manner the contents of the barrels are heated to a sterilizing temperature and maintained at such temperature for any required length of time.

65 When liquids evolving gases at a sterilizing temperature are treated, such gases collect in the gas-chambers 27, and in order to

avoid excessive pressures the rotation of the shaft 3 may from time to time be stopped when the pipes 18 and 19 are in a vertical position. The supply of heating agent is then temporarily cut off, the stop-cock in branch 7^a of exhaust-pipe 7 closed, and the stop-cock in the branch 7^b of said pipe opened, while the stop-cock 19 is set to cut off communication with pipe 31 and establish communication with its branch 19^b. If now the removable section 18^a is disconnected from pipe 18 and connected with pipe 19, as shown in Fig. 1, and the stop-cocks 23 and 24 opened, the gas in the gas-chambers 27 and the pressure-reducers 20 can be exhausted through exhaust branch 7^b and collected, if desired.

When the operation of sterilization is completed, the supply of heating agent is cut off 85 from the apparatus by closing stop-cock in branch 6^a of supply-pipe 6 and opening the stop-cock in branch 6^b of said pipe, thereby replacing the heating medium by a cooling medium to cool the contents of the barrels. 90

When the temperature of the contents of the barrels 8 and 8^a has been reduced from the sterilizing temperature to or about to atmospheric temperature and it is desired to carbonate said contents, the stop-cock in 95 branch 6^b, Fig. 3, of supply-pipe 6 is closed, the stop-cock in pipe 18 so set as to cut off the communication with pipe 29, Fig. 2, and establish communication with pipes 21 and 21^a, the pressure-reducers 20, and through 100 the gas-chambers 27 and the bungs with the interior of the barrels 8 and 8^a, the stop-cocks 23 and 24 being open, while the stop-cock 19^a of pipe 19 may or may not be closed, since the stop-cock 18^a when set as described cuts 105 the heating and cooling circuit out of the gas-supply circuit. The stop-cock in branch 6^c may now be opened and carbonic-acid gas under sufficient pressure admitted to the barrels until their contents are charged or saturated with gas, when the supply of the latter is cut off, the pressure-reducers and gas-chambers and bungs 34 and 35 are removed 110 from the barrels, and the latter bunged up in the usual manner and finally removed from 115 their supports.

It will of course be readily understood that the carbonation of the contents of the barrels may be materially expedited by revolving the barrels and that instead of carbonating the 120 liquid it may be simply aerated by connecting the branch 6^c with a source of supply of sterilized air under pressure.

To those conversant with the art of sterilizing liquids, and particularly malt liquids, the 125 apparatus described presents a great advantage over those hitherto used—namely, in that a special sterilizer is dispensed with and in that the burned taste imparted to malt liquids sterilized by means of a heating-coil 130 surrounded by the liquid in a stationary sterilizer is avoided, because the liquid in the apparatus described is continuously displaced or kept in motion about the circulating-coils

by revolving the barrels about a common axis and in that a special carbonating apparatus and the agitating devices commonly used are also dispensed with.

5. The apparatus has the further advantage of accommodating barrels of different capacities, and although I have shown and described barrels as holders for liquids to be sterilized or sterilized and carbonated it is obvious that holders of any other suitable construction may be secured to the supporting devices by suitably modifying the attaching appliances, such modifications being within the scope of the skilled mechanic.

15. Having thus described my invention, what I claim as new therein, and desire to secure by Letters Patent, is—

1. In apparatus such as described, a stopper for the filling-aperture of the vessel containing liquid to be treated having three passages, a coil of pipe constructed for introduction into such vessel through its said filling-aperture, and feed and exhaust pipes, said coil and feed and exhaust pipes respectively connected 25 with the inner and outer ends of two of said passages, means for feeding a heating or a cooling agent to said feed-pipe, a gas or vapor collector connected with the outer end of the third of the aforesaid passages, and means for 30 feeding a gas under pressure to said collector for the purposes set forth.

2. In apparatus such as described, a stopper for the filling-aperture of the vessel containing liquid to be treated having three passages, a 35 coil of pipe constructed for introduction into such vessel through its said filling-aperture, and feed and exhaust pipes, said coil and feed and exhaust pipes respectively connected with the inner and outer ends of two of said 40 passages, means for feeding a heating or a cooling agent to said feed-pipe, a gas or vapor collector connected with the outer end of the third of the aforesaid passages, means for 45 educating the gas or vapor collected in said collector, and means for feeding a gas under pressure to said collector, for the purposes set forth.

3. In apparatus such as described, a revoluble shaft, a support for the vessel containing liquid to be treated carried by the shaft, 50 a circuit for heating and a cooling agent having its initial and terminal at different points in the shaft, said circuit including a stopper for the filling-aperture of such vessel, and a 55 coil of pipe carried by the stopper and constructed to be introduced into the vessel through its said filling-aperture, and means for passing a heating or a cooling agent at will through said circuit, for the purpose set 60 forth.

4. In apparatus such as described, a revoluble shaft, a support for the vessel containing liquid to be treated carried by said shaft, a circuit for a heating and a cooling agent having 65 its inlet and outlet through said shaft, said circuit including a stopper for the filling-aperture of such vessel, and a coil of pipe con-

structed for introduction into said vessel through its filling-aperture, said stopper provided with a gas-passage, a branch circuit for 70 gas having its outlet in said gas-passage, means for cutting off communication between the inlet of said circuit and the aforementioned coil of pipe, means for establishing communication between said circuit-inlet and the branch circuit, means for passing a heating or a cooling agent at will through said circuit when open through said coil of pipe, and means for passing a gas through the branch circuit when open for this purpose, as set 80 forth.

5. In apparatus such as described, a revoluble shaft, a support for the vessel containing liquid to be treated, carried by said shaft, a main circuit for a heating or a cooling agent having its inlet and outlet through the shaft, said circuit including a stopper for the filling-aperture of such vessel and a coil of pipe constructed for introduction into said vessel through its filling-aperture, said stopper provided with a gas-passage, a branch circuit for 85 gas having its outlet in said gas-passage and including a gas-collector, means for cutting the branch circuit out of the inlet side and connecting it with the outlet side of said main circuit to exhaust the gas collected in said collector, and means for passing a heating or a cooling agent at will through the main circuit, for the purpose set forth.

6. In apparatus such as described, a support for the vessel containing liquid to be treated, carried by said shaft, a main circuit for a heating and a cooling agent having its inlet and outlet through the shaft, said circuit including a stopper for the filling-aperture of such vessel and a coil of pipe constructed for introduction into said vessel through its filling-aperture, said stopper provided with a gas-passage, a branch circuit for 90 gas having its outlet in said passage, and including a pressure-reducer and a gas-expansion chamber, means for cutting off communication between the inlet of the main circuit and the aforesaid coil of pipe, and for establishing communication between said inlet and the branch circuit, means for passing a heating or a cooling agent at will through the main circuit when open, and means for passing a gas through the branch circuit when open, for the purpose set forth.

7. In apparatus such as described, the combination with the revoluble shaft 3, the base-plate 9 carried thereby and having internally-threaded sleeves on opposite sides of its longitudinal center, a chain on opposite sides of 105 said sleeves connectible with said base, a pair of skids, and tightening-screws working in the aforesaid sleeves against said skids, for the purpose set forth.

8. In apparatus such as described, the combination with the revoluble shaft 3, a support for barrels comprising a bracket carried by the shaft and having two pairs of arms, the arms of a pair extending in opposite directions 110

from the bracket, a head-plate on each side of said bracket on which the latter and its arms have bearing, said head-plates having sleeves fitting one of the heads and stave ends 5 of the barrels, similar head-plates for the opposite heads of the barrels, clamping-plates applied to the last-named head-plates, cross-heads provided with an internally-threaded opening connecting- rods connecting said 10 cross-heads with the aforesaid arms of the brackets, and clamping-screws working in said openings and having bearing on said

clamping-plates, substantially as and for the purpose set forth.

9. In apparatus such as described, the 15 head-plate 14 having two radial arms 14^a and shoes 14^b having sliding motion on said radial arms, for the purpose set forth.

In testimony whereof I affix my signature in presence of two witnesses.

CAMILLE AMEYE.
